(57) **CLAIM**

The ornamental design for a display screen with graphical user interface, as shown and described.

DESCRIPTION

FIG. 1 is a front view of a display screen with graphical user interface showing our new design;

FIG. 2 is a rear view of the display screen with graphical user interface incorporated in a portable device;

FIG. 3 is the left side view thereof;

FIG. 4 is the right side view thereof;

FIG. 5 is the top image thereof; and,

FIG. 6 is the bottom view thereof.

The broken lines around and within FIGS. 1-6 show a display screen thereof and unclaimed portions of the graphical user interface and form no part of the claimed design.
